UNITED STATES PATENT OFFICE

166,856

POSTAL SCALE

Stan B. Hanssen, Kenilworth, and Lucille E. Hansen, Barrington, Ill., assignors to Hanson Scale Company, Chicago, Ill., a corporation of Illinois

Application March 13, 1952, Serial No. 18,872

Term of patent 14 years

(Cl. D52—10)

To all whom it may concern:

Be it known that we, Stan B. Hanssen and Lucille E. Hansen, citizens of the United States of America, residing respectively at Kenilworth, county of Cook, State of Illinois, and Barrington, county of Lake, State of Illinois, have invented a new, original, and ornamental Design for a Postal Scale of which the following is a specification, reference being had to the accompanying drawings, forming a part hereof.

Fig. 1 is a front perspective view of a postal scale, showing our new design; and

Fig. 2 is a rear perspective view thereof.

We claim:

The ornamental design for a postal scale, substantially as shown.

STAN B. HANSEN.
LUCILLE E. HANSEN.
